FOOTWEAR

Edwin Calvin, Akron, Ohio

Application April 21, 1937, Serial No. 138,204

1 Claim. (Cl. 36—8.5)

This case relates to footwear.

The general purpose of the invention is to provide a simple, economical, footwear construction with an improved rubber or like sole whereby the foot is correctly and comfortably supported in the shoe.

The foregoing and other purposes of the invention are attained in the shoe sole illustrated in the accompanying drawings and described below.

It is to be understood that the invention is not limited to the specific form thereof shown and described.

Of the accompanying drawings:—

Figure 1 is a bottom perspective of footwear embodying the invention.

Figure 2 is a top plan of the sole used therein.

Figure 3 is a section on line 3—3 of Figure 2.

Figure 4 is a section on line 4—4 of Figure 2.

Referring to the drawings, the numeral 10 designates a shoe upper to which is secured, as by stitching 11 about the margins of the sole and nails 12, 12 in the heel portion, a rubber sole 13.

The sole 13 may be formed on its upper margins as at 14 to simulate welting and at the inside 25 of the shank of the sole on the top thereof there is provided an integral raised portion 14^a to support the arch of the foot. On the bottom of the sole at the shank under the raised portion 14^a there is preferably formed a recess 15 whereby 30 the edge of the sole at the inside of the shank will be substantially of uniform thickness with the rest of the sole edge. The stitching 11 extends into the recess 15 and serves to draw the arch-supporting formation 14^a well up into the bottom of the shoe.

This is shown in Figure 4, the numeral 16 designating the usual in-sole associated with the upper.

As shown in Figures 2 and 3 the upper face of the sole may also be provided with a metatarsal

support 17 comprising a mound of rubber integral therewith and so positioned with respect to the arch support 14^a as to correctly position the foot in the shoe.

The raised portions 14^a and 17 on the upper face of the shoe are effective upon the in-sole 16 to shape it to the bottom of the foot so as to support the foot comfortably and correctly in the shoe. By providing either or both of the formations 14^a and 17 in an integral sole construction, 10 this is accomplished simply and economically.

Modifications of the invention may be resorted to without departing from the spirit thereof or the scope of the appended claim. It will be apparent that the improved sole may be secured to the 15 upper by nails or cement instead of, or in addition to, the stitching 11.

What is claimed is:

Footwear comprising an upper and an insole, 20 and a rubber out-sole attached thereto, said out-sole comprising an integral one-piece molded construction formed with a raised mound-like arch-supporting formation thereon at the top of the sole and at the inside margin of the shank, said sole being formed with a marginal recess at 25 the inside margin of the shank on the bottom thereof directly beneath said arch-supporting formation, whereby the inside edge of the shank is substantially uniform in thickness with the rest of the sole, said sole being stitched to said upper 30 about the marginal portion thereof by a line of stitches extending into said marginal recess, said stitches in said recess serving to hold the arch-supporting formation up into the bottom of the 35 footwear and support the insole over said arch-supporting formation.

EDWIN CALVIN.
